BRUSH APPLICATOR FOR A SQUEEZE BOTTLE

Joseph F. Quaas, Island Park, N.Y., and Paul H. Smith, Hopkins, Minn., assignors to Eutectic Welding Alloys Corp., Flushing, N.Y., a corporation of New York

Application March 5, 1959, Serial No. 54,863

Term of patent 14 years

(Cl. D9—2)

Fig. 1 is a top plan view of a brush applicator for a squeeze bottle, showing our new design;

Fig. 2 is a front view in elevation of the article shown in Fig. 1; and

Fig. 3 is a side view in elevation of the article shown in Fig. 1.

The dominant features of our design reside in the portions shown in full lines.

We claim:

The ornamental design for a brush applicator for a squeeze bottle, as shown and described.
